UNITED STATES PATENT OFFICE.

BENJAMIN N. BLACK, OF PATERSON, NEW JERSEY.

BLACKBOARD-LINER.

1,202,780.

Specification of Letters Patent. Patented Oct. 31, 1916.

Application filed April 4, 1916. Serial No. 89,465.

To all whom it may concern:

Be it known that I, BENJAMIN N. BLACK, a citizen of the United States, residing at Paterson, in the county of Passaic and 5 State of New Jersey, have invented certain new and useful Improvements in Blackboard-Liners, of which the following is a specification, reference being had therein to the accompanying drawing.

10 One object of my invention is to provide a rapid and reliable liner for blackboards which will make a number of parallel lines or concentric circles in various relative positions by means of marking-crayons or other 15 marking materials without regard to the differences in length of the crayons and to produce a holder for the crayons in which they may be arranged and adjusted with ease and facility and in which they may 20 be tilted without slipping when in use.

A further object of my invention is to provide a device that will be an aid to the teacher in blackboard illustration and that may be taken apart and put together quickly 25 and which when taken apart may be handily packed in a small parcel for shipping or mailing purposes.

30 A further object of my invention is to provide grooved fingers, pivotally secured to the main body, each finger being independent of the others and having elastic means for controlling the tilting movement of its individual crayon, while in use, in the groove wherein it is held.

35 A still further object of my invention is to produce a blackboard-liner simple in construction, practical, durable and cheap.

The accompanying drawings illustrate my 40 invention, similar letters of reference in the various figures indicating like parts.

Figure 1 is a plan view of the bottom of my blackboard-liner, the crayons being held in position in the longitudinal grooves in the fingers by their respective elastic bands 45 or cords, which pass over the crayons and through the transverse grooves in the top of the fingers. Fig. 2 is a vertical sectional view on the line 2—2 of Fig. 1, showing the arrangement of the finger, crayon and elastic band. Fig. 3 is a view in cross section on the line 3—3 of Fig. 1, further showing the method of holding the crayon in the finger. The dotted lines in Fig. 1 show the

pivotal movement of the fingers, and the dotted lines in Fig. 2 illustrate the tilting 55 of the crayon when in use.

In the drawings, A is the main or body portion; A¹ are the fingers, A² the longitudinal grooves in the fingers, A³ the transverse grooves in the fingers to receive the 60 elastic band or cord, B the handle, C the crayons, E the elastic bands or cords and S the pivot screws securing the grooved finger to the body portion A.

It is obvious that crayons, pencils, brushes 65 or other marking materials or devices may be used in the longitudinally grooved fingers, if desired. In each instance the elastic band will hold the article used in position and permit it to be tilted, the end of the 70 finger forming a fulcrum. The crayon may be moved longitudinally in the grooved finger as long as it lasts.

If it is desired to use only the two end 75 crayons, the intervening crayons may be pushed back out of action. Owing to the pivotal arrangement of the fingers, they may be moved toward or away from each other, as desired, to regulate the space between 80 lines or between concentric circles.

In teaching music, writing, bookkeeping, arithmetic, geometry, and other subjects 85 this liner will be of great utility, as two or more lines may be drawn parallel in any direction and circles and arcs in various relative positions, as above stated. An advantage quite apparent with my invention is the fact that the handle may be removed and folded up with the stock or body, when it makes a small neat package easily han- 90 dled, shipped, or mailed. The tautness of the elastic band is regulated with ease and facility. The elastic band or cord permits the use of crayons of unequal length, as it yields gently to the pressure necessary 95 to cause the crayons to tilt and trace the lines or figures desired. The tautness of the elastic band may be regulated by giving the elastic band one or more extra wraps around the finger. The ends of the handle 100 are pressed toward each other to insert them in the holes in the body portion which receives them, and the tension thus secured is sufficient to retain the handle in the body portion for ordinary purposes. By pressing 105 the ends of the handle, the tension is re-

moved sufficiently to allow the withdrawal of the handle from the body portion with facility.

5 The crayon may be utilized to the same extent as if used by hand.

With this description of my invention, what I claim is:

1. In a blackboard-liner, a body portion having a removable handle, in combination 10 with a plurality of fingers pivotally secured to the body portion, and longitudinally grooved on their under sides, each groove forming a receptacle for a crayon or the like, each finger having on its upper face, near 15 the free end thereof, a transverse groove to hold an elastic retainer, and an elastic retainer passing through said transverse groove and around the crayon, substantially as set forth.
- 20 2. The body portion, in combination with a plurality of longitudinally grooved fingers, pivotally secured thereto, a plurality of crayons or other marking articles adapted to be held in the grooves of the fingers 25 and each finger having elastic means independent of the other fingers and adapted to hold the crayon in the finger groove and permit the crayon to tilt, substantially as set forth.

Copies of this patent may be obtained for five cents each, by addressing the "Commissioner of Patents. Washington, D. C."

3. A blackboard-liner comprising a body 30 portion, and a plurality of fingers pivotally secured thereto, each finger having on one face a longitudinal groove adapted to hold a marking article, and on its opposite face a transverse groove adapted to hold an elastic retainer, and an elastic means adapted 35 to pass through said transverse groove and around the marker to hold the same in the groove in the finger and to permit it to tilt when in use, substantially as set forth. 40

4. In a blackboard-liner, a pivotally arranged finger longitudinally grooved on its under surface to form a receptacle for a marking material, and provided on its upper face with a transverse groove adjacent to 45 the tip of the finger, adapted to hold an elastic material and an elastic retainer passing through said groove on the upper face of the finger and around the marking material to permit the marking material to be 50 tilted, the end of the finger forming a fulcrum.

In testimony whereof I affix my signature in presence of two witnesses.

BENJAMIN N. BLACK.
